UNITED STATES PATENT OFFICE

CLARENCE B. IRVING, OF KANSAS CITY, MISSOURI, ASSIGNOR TO WILSON-JONES COMPANY, OF CHICAGO, ILLINOIS, A CORPORATION OF MASSACHUSETTS

LOOSE LEAF MEMORANDUM BOOK

Application filed January 28, 1932. Serial No. 589,364.

This invention relates to loose leaf binders and particularly to memorandum books having loose leaf features and including a novelly constructed filler which cooperates with the sheet-holding means of the binder in a manner whereby an especially large number of sheets may be included in the filler without crowding the holding prongs of the sheet-holding means.

10 Another object of this invention is the contemplation of a unique filler for loose leaf memorandum books, which filler comprises a plurality of filler units, each having a predetermined number of sheets therein 15 releasably and temporarily held together until the sheets of the filler unit are drawn apart by a normal "leafing" of the entire filler.

A still further object of the instant invention is to provide a filler sheet for loose leaf memorandum books which has a series of 20 equally spaced tabs of equal width at the binding margin thereof, the tabs of adjoining sheets of the filler being in offset relation, whereby to cause a binder metal of 25 given size to support a substantially greater number of sheets than would be possible under normal conditions.

It is known in the art that extremely light 30 memorandum books usually do not have the loose leaf feature. That is to say, a sheet of the memorandum book filler cannot be removed from the sheet-holding means without actual tearing out. Another of the inherent short comings of the loose leaf memorandum book is the exceptionally great 35 size of the binder metal compared to the thickness of the filler which the metal can support, yet allow free manipulation of the 40 sheets.

It is an object of this invention, therefore, to provide a loose leaf memorandum book to overcome the objections just set down and which provides the aforementioned features by combining a specially formed filler sheet with a novel filler-holding means, whereby the number of sheets operably supported by prongs or rings of a given diameter is practically doubled.

50 A yet further object of the instant inven-

tion is the contemplation of a filler unit for loose leaf memorandum books, the sheets of which unit are temporarily and releasably held together to facilitate inserting the unit in a memorandum book.

Minor objects of this invention will appear during the course of the specification, referring to the accompanying drawing, wherein:

55 Figure 1 is a perspective view of a loose leaf memorandum book embodying the features of this invention.

Fig. 2 is a fragmentary face view of the binding-margin end of a filler sheet formed in accordance with the invention.

60 Fig. 3 is a similar view of the same sheet, except that the view is of the opposite side.

Fig. 4 is an edge elevation of a filler unit showing the position of the means for temporarily maintaining the sheets thereof in 70 assembled relation.

Fig. 5 is a fragmentary face view of the 75 filler unit shown in Fig. 4.

Fig. 6 is an enlarged fragmentary sectional view through a portion of the memorandum book and its filler.

Fig. 7 is a fragmentary edge elevation of the closed binder, and

Fig. 8 is an enlarged top plan view of the sheet-holding means adapted for use with 80 the sheets illustrated in Figs. 2 and 3.

The binding material for a memorandum book embodying this invention might be of any suitable substance, and while the cover has herein been illustrated to be flexible in 85 nature, it is understood that the binding for these memorandum books might be altered to suit the taste.

In the drawing, sides 10 are joined by a back portion 12, to which is affixed the sheet-holding means for carrying the complete 90 filler 14. In this instance the sheet-holding means comprises a pair of coating metal parts of a character illustrated in Fig. 8. Stationary rib 16 lies against the inner surface of back portion 12 and is secured in place by rivets 18 and 20 at each end, respectively of stationary rib 16. These rivets 18 and 20 pass through back portion 12 95 and engage back plate 22 in a manner which 100

distributes pressure throughout the width of the binder. Swingable rib 24 overlies stationary rib 16 when the sheet-holding means is in a closed position and rib 24 5 pivots about a point adjacent one of its ends when it is desired to part the ribs to insert or remove sheets of filler 14. Rivet 20 pivotally supports swingable rib 24 by passing therethrough while rivet 18 at the opposite 10 end of the two ribs 16 and 24 contributes toward creating an effective means for yieldably maintaining the two ribs in closed relation. A resilient tongue 26 is formed integrally with rib 16 and is rebent thereover 15 transversely thereof in spaced relation thereto so that the head of rivet 18 lies between tongue 26 and rib 16. A detent 28 is embossed in swingable rib 24 to engage the head of rivet 18 when the end of rib 24 is forced beneath tongue 26. An upturned lug 30 formed on rib 24 affords a thumbnail engageable member whereby to move rib 24 to and from the closed position. A series of 20 mating prongs 32 having inclined ends 34 are equally spaced apart throughout the length of rib 24 and cooperate with a series of like prongs 36 formed on rib 16. Prongs 36 likewise have inclined ends 38 which are complementary to the ends 34 of prongs 32 25 and when the two ribs are brought together as shown in Figs. 1, 6 and 7, there is formed a series of complete mating prongs throughout the length of sheet-holding means which are capable of receiving a novelly constructed 30 filler 14.

In carrying out one of the concepts of this invention, the filler 14 of the loose leaf memorandum book is made up of a number of filler units 40, each comprising a predetermined number of sheets 42 releasably and temporarily held together by narrow strips of transparent binding or padding adhesive 44, disposed across the edge of each unit adjacent the binding margin thereof 45 substantially as illustrated in Figs. 4 and 5. In applying this binder 44, a large number of sheets 42 may be stacked in superimposed relation, the binder applied in any desired manner and then the large stock divided into 50 filler units for insertion into the loose leaf book. The number of sheets included in each filler unit 40 may vary in accordance with the sheet size. The use of such units allows quicker insertion of a number of sheets in a small binder and where the sheets are formed as herein contemplated, the binder maintains the several sheets 42 of the unit 40 in proper relation. With respect to the construction of the individual sheet 42, the 55 entire filler 14 is made up of superimposed sheets 42 having a binding margin formed as illustrated in detail in Figs. 2 and 3. Sheets having binding margins of this character allow a sheet-holding means to receive 60 a filler having practically twice as many

70 sheets as would be possible with an ordinary filler. Each sheet 42 has a binding margin made up of a series of spaced-apart tabs 46, each tab having a slot 48 formed therethrough for the reception of the aforementioned prongs of the sheet-holding means. Tabs 46 are of equal width and are equally spaced apart, and while slots 48 of any one sheet 42 are being engaged by every other prong 32 and 36, the intermediate 75 prongs 32 and 36 pass between tabs 46 of that particular sheet to engage the slots 48 and tabs 46 formed at the binding margin of the next adjoining sheet 42.

75 In the manufacture of sheets 42, the same may have their binding margins formed alike so that a tab 46 is at one edge thereof, while a tab 46 at the opposite edge thereof is spaced therefrom a distance equal to the width thereof. In other words, the sheet is turned over to cause the tabs 46 to be in offset relation with the tabs 46 of the sheet next adjoining. Maintaining the width of tabs 46 and the distance between the same substantially identical presents an unbroken 80 binding margin in so far as appearance is concerned. There are no gaps to be seen when viewing the filler and its binding margin appears to be the same as the binding margin of the ordinary filler without the especially formed margin. Mating prongs 85 32 and 38 may be filled to capacity, as illustrated in Figs. 6 and 7, yet when any part of the filler is turned from one cover of the binder toward the other, the freedom required at the binding margin is afforded by movement of tabs 46 into the spaces therebetween.

90 Since the sheets 42 of each filler unit 40 are maintained in proper relation by the binder 44, and in view of the fact there are but five or six of these filler units 40 in a complete filler 14, it is virtually impossible to load the sheet-holding means in any but the proper manner. In other words, regardless of how the filler 14 is placed upon prongs 32 and 36, it is possible to have a 95 filler of substantially twice the number of sheets as would be possible with a filler having the ordinary binding margin.

100 The binder 44 holds the sheets 42 of each filler unit 40 just enough to keep them from offsetting or coming apart during handling up to the time the insertion is completed. After this, turning of the individual sheets 105 42 will immediately cause them to break apart and binder 44 becomes non-effective.

110 Having thus described the invention, what is claimed as new and desired to be secured by Letters Patent is:

115 1. In a loose leaf memorandum book, sheet holding means; a filler carried by said means comprising a plurality of filler units, each unit including a number of superimposed sheets all engaged by the holding means;

and binding means comprising a narrow strip of adhesive at the edge of each unit for releasably maintaining the sheets thereof in associated relation.

- 5 2. In a loose leaf memorandum book, sheet-holding means; a filler carried by said means comprising a plurality of filler units, each unit including a number of superimposed sheets, each sheet of a unit having a 10 binding margin of a series of spaced-apart tabs, the tabs of adjoining sheets being in offset relation; and binding means across each side edge of a unit adjacent said binding margin to maintain the tabs of the unit 15 sheets in proper offset relation.
3. In a loose leaf memorandum book, a filler comprising a number of superimposed filler units; and means at the edge of each filler unit for temporarily holding together 20 the several sheets of each unit, said means comprising a narrow transverse strip of material separably secured to each filler unit on opposite side edges and near one end thereof.
- 25 4. In a loose leaf memorandum book, a filler comprising a number of superimposed filler units; releasable means for temporarily holding together the several sheets of each filler unit; and a series of equally spaced 30 tabs of equal width at the binding margin of each unit sheet, said releasable holding means being across an edge thereof adjoining the binding edge and adjacent thereto.
5. A filler for loose leaf books comprising 35 a plurality of superimposed sheets; and means setting off within said filler units of a predetermined number of said sheets, said means temporarily holding together the sheets of each unit and consisting of a narrow strip of adhesive extending transversely across opposite edges of each unit near one end thereof.
- 40 6. A filler for loose leaf books comprising a plurality of superimposed sheets; and 45 means setting off within said filler units of a predetermined number of said sheets, said means temporarily holding together the sheets of each unit, and consisting of a relatively narrow strip of transparent padding 50 adhesive along an edge of each unit adjacent the binding margin thereof.
7. A filler for loose leaf books comprising a plurality of superimposed sheets; and 55 means setting off within said filler units of a predetermined number of said sheets, said means temporarily holding together the sheets of each unit, and consisting of a relatively narrow strip of padding adhesive along opposite edges of each unit at a point 60 spaced apart from the binding margin thereof.

In testimony whereof, I hereunto affix my signature.

CLARENCE B. IRVING.
